UNITED STATES PATENT OFFICE.

LE ROY ROOT, OF BROOKLYN, NEW YORK, ASSIGNOR TO SCOVILL MANUFACTURING COMPANY, A CORPORATION OF CONNECTICUT.

POWDER BOX.

Application filed July 27, 1922. Serial No. 577,795.

This invention relates to certain improvements in small boxes for containing loose powder, such as toilet powder and the like.

These boxes are largely used by ladies for carrying face powder and should be of a size and shape to conveniently fit in a hand bag, pocketbook, or the like, and the boxes are generally capacitated to hold a powder puff or the like for applying the powder. 10 The users of toilet powder prefer to use the powder in a loose condition, as the powder in this form is purer and more readily taken up by the puff and applied. If, however, the powder is carried loosely in the boxes with a puff, waste occurs by spilling of the powder either when the puff is used to take it from the box, or because of the box becoming accidentally opened. Furthermore, most users have a particular brand of powder which they prefer to use, and want a box that can be readily refilled without loss of powder.

It is the especial object of the present invention to provide an improved powder box 25 of simple form so that it can be very cheaply produced and of convenient shape for carrying in a hand bag, pocketbook, or the like, which is leak proof, that is, the box is so formed that escape of powder is prevented except through the discharge orifices provided for the purpose, and which box shall be so formed that it may be readily refilled by the user with loose powder as desired.

With this and other objects in view, not 30 specifically referred to, the invention consists in certain novel parts, arrangements and combinations, a detailed description of which will be given in connection with the accompanying drawings, and the novel features thereof pointed out in the claim hereunto annexed.

In these drawings:

Figure 1 is a vertical sectional view of the improved box.

45 Figure 2 is a sectional plan view of the construction shown in Fig. 1, the section being taken on line 2-2 of that figure.

Figure 3 is a vertical sectional view taken on the line 3-3 of Fig. 1.

50 Figure 4 is a detail sectional view showing the cover and bottom removed.

Figure 5 is a detail sectional view of the removable bottom of the box.

The box will be constructed so as to have

as few parts as possible so as to cheapen the 55 manufacture. While the box may be of any desired size or shape, the box as shown, is of a size convenient to fit a hand bag, pocketbook, or the like, and may be circular in form, and the various parts of the box will 60 preferably be made of light or thin sheet metal as brass. The improved box comprises, where a circular shape is adopted, what may be termed a ring 1, which is open 65 at both ends and forms the body portion of the box. This ring 1 has secured therein, in any suitable manner, as by soldering, a dispensing or sifting member in the form of a plate 2, this plate being preferably curved 70 downwardly toward the bottom of the box, 70 as indicated at 3, and provided with a plurality of discharge orifices 4, suitably arranged preferably around the inner or central portion of the plate. With this construction any loose powder above the plate 75 will tend to gravitate toward the center of the plate and pass back into the box through the orifices. This plate 2 is disposed in the ring 1 preferably intermediate the ends of 80 the ring so as to leave above it a space which 80 will accommodate a powder puff or the like 5, this puff being held in position by a cover 6.

The box is so constructed and arranged 85 that it may be readily refilled with loose powder and the parts are so constructed that the box is leak proof, that is, so that no powder can escape from the box except through the discharge orifices 4 when it is desired to dispense the powder.

90 While various constructions may be employed for this, in the best constructions there is provided a removable bottom member 7, and this bottom member is provided with an upwardly extending collar or flange 95 8 arranged to snugly fit within the lower part of the ring 1 below the dispensing plate 2. To prevent leakage there is provided in the ring an abutment against which the flange 8 of the container bottom 7 may abut 100 so as to prevent powder leaking past it and escaping from the box. While this abutment may be formed in various ways, a simple and effective one is that illustrated, in which the plate 2 is formed with a downwardly extending peripheral skirt or flange 9 against the lower edge of which the upper edge of the collar 8 on the bottom 7 abuts 105

inside the ring so as to form a tight joint and prevent the leakage of powder past these parts.

In the best construction the container bottom 7 will be provided with means for holding it in place. While these means may be somewhat varied, in the particular construction illustrated, the bottom is provided with humps 10 adapted to take in to angled slots 11 formed in the ring 1. The bottom container 7 is also, in the best constructions, provided with a round 12 by which it may be readily grasped for rotating it to free it from the lock when it is to be removed from the ring for refilling with powder.

The cover 6 may be secured in position in any desired manner. In the construction illustrated this cover is, as shown, a hinged cover, being hinged to the ring 1 at 13, and at its opposite side is provided with a catch 14 taking over a hump 15 on the ring 1.

With the construction described a very simple and cheap box has been provided and one consisting of few parts and which may be readily stamped from metal, and the parts of which may be readily and quickly assembled, thus providing a very economical container. This container, furthermore, can be quickly and easily refilled with loose powder, and this loose powder is prevented from getting out of the box except through the discharge orifices in the dispensing plate.

While the invention has been shown and described in its preferred form, it will be

understood that certain changes and variations may be made in the specific structure disclosed without departing from the invention.

What I claim is:

A dispensing box for loose powder comprising an annular body member of thin light metal open at each end and consisting of a cylindrical ring provided intermediate its ends with an outwardly extending bead, a perforated distributing plate arranged in the body member below said bead and having a downwardly extending annular skirt snugly engaging the inner cylindrical surface of said body member, a cover for the box spaced from the plate to accommodate a powder puff between the plate and cover, said cover having a depending annular skirt adapted to snugly engage the upper cylindrical portion of the body member and to abut against said bead, and a removable bottom having a continuous upstanding flange telescopically engaging the lower cylindrical portion of the body member and abutting against the lower edge of the skirt of the distributing plate, so as to prevent leakage of the powder from the box except through the perforations of the distributing plate, said bottom also having an outwardly extending annular bead abutting against the lower edge of the body member.

In testimony whereof, I have hereunto set my hand.

LE ROY ROOT.
